UNITED STATES PATENT OFFICE.

GEORGE L. BORDEN, OF GROVEVILLE, NEW JERSEY.

DESIGN FOR A TUMBLER OR SIMILAR ARTICLE.

47,216.

Specification for Design.

Patented Apr. 13, 1915.

Application filed January 30, 1915. Serial No. 5,330. Term of patent 7 years.

To all whom it may concern:

Be it known that I, GEORGE L. BORDEN, a citizen of the United States, residing at Groveville, in the county of Mercer and State of New Jersey, have invented a new, original, and ornamental Design for a Tumbler or Similar Article, of which the following is a specification, reference being had to the accompanying drawing, forming part thereof.

Figures 1 and 2 are elevations at right angles to each other, of a tumbler or similar article embodying my design.

I claim:

The ornamental design for a tumbler or similar article, as shown.

GEORGE L. BORDEN.
